UNITED STATES PATENT OFFICE.

JAMES H. SHAW AND EDGAR B. BOYER, OF JOHNSTOWN, PENNSYLVANIA.

METALLIC TIE AND RAIL-FASTENER.

No. 893,388.

Specification of Letters Patent. Patented July 14, 1908.

Application filed March 12, 1908. Serial No. 420,703.

To all whom it may concern:

Be it known that we, JAMES H. SHAW and EDGAR B. BOYER, citizens of the United States of America, residing at Johnstown, in the county of Cambria and State of Pennsylvania, have invented certain new and useful Improvements in Metallic-Ties and Rail-Fasteners, of which the following is a specification, reference being had therein to the accompanying drawing.

This invention relates to metallic ties and rail fasteners, and the objects of our invention are, first, to provide a simple and inexpensive metallic tie for supporting rails; second, to provide a metallic tie wherein a novel fastener is employed for firmly retaining the rails thereon and preventing vertical and lateral displacement of the same; and third, to provide a tie of a novel double Z constructed of Z-bars arranged and secured together whereby the tie can be easily ballasted in a road bed.

We attain the above objects by a construction that will be presently described and then specifically pointed out in the appended claims.

Referring to the drawing forming a part of this specification, Figure 1 is a perspective view of one end of our tie, Fig. 2 is an end view of the same, Fig. 3 is a longitudinal sectional view of a portion of the tie, Fig. 4 is a perspective view of one of the rail fasteners, and Fig. 5 is a perspective view of a bolt block.

To put our invention into practice, we employ two double Z-bars, which are connected to provide a substantial oblong tie. The configuration of the Z-bars and the manner in which they are connected provides a tie of considerable rigidity and strength, capable of withstanding downward pressures exerted by rolling stock passing over the same. Each bar used in connection with our tie comprises a large Z portion 1 and a small Z portion 2, the latter being superposed and cut away contiguous to its ends, as at 3, to permit of rails 4 resting upon the large Z portions. The small Z portions 2 of the bars provide a triangular compartment 5 for similarly shaped rail fasteners 6, these fasteners extending over the base flanges of the rails 4. To retain the rail fasteners 6 in position to brace the web portion of the rails, we use bolts 7, these bolts passing through the small Z portions of the bars and the compartment 5 at the outer ends of the rail fasteners 6,

whereby it will be impossible for said fasteners to move in the compartment 5 due to any stresses or strains upon the rails 4.

In order that the bolt 7 can be secured in the tie, we use triangular bolt blocks 8, these blocks engaging the outer sides of the Z portions of the bars and providing flat surfaces for the heads 9 of said bolts and the nuts 12 secured thereon.

From the foregoing description taken in connection with the drawings, it will be observed that the bars comprising the tie can be easily rolled and secured together by the bolts 7 and the nuts 12, which also serve to retain the rail fasteners 6 within the ties and in engagement with the rails mounted thereon.

Having now described our invention what we claim as new, is:

1. In a metallic tie and rail fastener the combination with rails, of double Z-bars having large Z portions and superposed small Z portions, said small Z portions being cut away to provide seats for said rails upon said large Z portions, said small Z portions providing triangular frames, rail fasteners mounted in said frames and engaging said rails, bolts extending through said frames for holding said rail fasteners in position and connecting said double Z bars together, triangular blocks engaging said small Z portions for providing flat surfaces for the heads of said bolts, and nuts screwed upon said bolts.

2. In a metallic tie and rail fastener, the combination with rails, of double Z-bars, said double Z-bars having large Z portions, and superposed small portions, said small Z portions being cut away to provide seats for said rails upon the large Z portions of said bars, triangular rail fasteners mounted between the small Z portions of said bars, and means for simultaneously connecting said bars together, and retaining said rail fasteners in engagement with said rails.

3. In a metallic tie and rail fastener, the combination with rails, of double Z-bars adapted to be connected together, said bars having large Z portions and small Z portions, said small Z portions being cut away to provide seats for said rails upon said large Z portions, and rail fasteners detachably mounted in said small Z portions for retaining said rails in engagement with said tie.

4. In a metallic tie and rail fastener, the combination with rails, of double Z-bars connected together, said bars comprising

large **Z** portions, and small **Z** portions, said small **Z** portions being cut away to provide seats for said rails upon said large **Z** portions, and means located in the small **Z** portions of said tie for holding said rails in engagement therewith.

5. In a metallic tie, the combination with rails, of double **Z**-bars connected together for supporting said rails, said bars comprising large **Z** portions, and superposed small **Z** portions, said small **Z** portions being cut away to provide seats for said rails upon said large **Z** portions.

6. A metallic tie comprising double **Z**-bars adapted to be connected together, said bars comprising large **Z** portions with small superposed **Z** portions, substantially as described.

15. In testimony whereof we affix our signatures in the presence of two witnesses.

JAMES H. SHAW.
EDGAR B. BOYER.
